United States Patent Office.

GEORGE A. SEAVER, OF NEW YORK, N. Y.

Letters Patent No. 96,624, dated November 9, 1869.

IMPROVED LATCH.

The Schedule referred to in these Letters Patent and making part of the same.

I, GEORGE A. SEAVER, of New York, in the county and State of New York, have invented certain Improvements in Locks, of which the following is a specification.

Nature and Objects of the Invention.

The first part of my invention relates to the change of position of the latch-bolt, by which the lock may be used either as a right or left-hand lock, without removing the spindle, or otherwise disturbing the interior.

The second part of my invention relates to the mechanism operated by the key, by which the connection between the handle and the bolt may be established or broken, as may be desired.

Description of the Drawing.

The drawing shows a rim-lock, of which the plate has been removed, for the exhibition of the internal parts.

The Latch.

The spindle *a* operates the latch-tail *b* by means of a follower, *c*, acting in opposition to a spring, *d*, in the usual manner.

The latch-bolt *e* is carried by a swivel on the latch-tail, that admits of its being turned to face in either direction; and where the swivel is made of a screw, the projection of the latch may also be regulated as may be required.

The screw *f*, that passes through the outer face of the lock, prevents the passage of the latch entirely through the plate of the lock, and, therefore, prevents the turning of the latch; but when it is removed, the latch and latch-tail may be drawn forward until the latch can be turned on its swivel in either direction, and screwed in or out, as may be desired.

The screw *f* may be one of the screws by which a rim-lock is secured to a door; and in a mortise-lock, it may be a separate screw, provided for the purpose.

The follower *c* is not fastened to the spindle in the ordinary manner, but is slotted, or otherwise arranged, for the reception of the spindle, in such a manner, that although the turning of the spindle turns the follower, to operate the latch-tail, the latter may be drawn forward, to change the latch, without removing the spindle.

The Key.

That part of the said invention by which the locking and unlocking are effected, consists in detaching the spindle from the follower, by drawing the latter forward with the key, so that the handle and spindle may be freely turned without moving the latch-tail and latch.

When unlocked, the spring *g* throws the follower *c* back upon the spindle, as shown in the drawing, so that the three sides of the rectangular portion of the recess of the follower fit around the square shaft of the spindle, and enable the latter to turn the former, and operate the latch, as usual.

The turning of the key moves the sliding tumbler *h*, which bears against the spring *g*, and carries it and the follower forward, so that the square recess of the latter is relieved from the spindle, and the handle permitted to turn, without affecting the latch.

The latch may be retracted, by the closing of the door, after the key has been turned, but it is entirely clear of the spindle; and the handle may be turned, to try the bolt, without disturbing or straining any of the parts of the lock.

The movement of the key may be accompanied by the movements of additional tumblers, that may also be applied to the tail of the latch, to hold the bolt in position, when detached from the spindle, by a positive attachment, in addition to its spring.

Care must be taken to have the screw *f* and other parts of the lock in their proper places.

Claims.

I claim, as my invention—

1. The follower, made for the reception of the spindle, with a recess, substantially as described, one part of which fits the spindle, and the other permits the spindle to turn freely therein.

2. The combination of a latch with the sliding follower, so that the latch may be reversed without removing the spindle.

3. The combination of a sliding follower with the mechanism of a lock, operated by the key, in such a manner that the turning of the key connects or detaches the spindle and the latch, as may be required.
